UNITED STATES PATENT OFFICE.

MARCUS RAY COWELL, OF WINNIPEG, MANITOBA, CANADA.

HARNESS GIRTH-CONNECTING MEANS.

Application filed March 14, 1923. Serial No. 625,124.

To all whom it may concern:

Be it known that I, MARCUS RAY COWELL, a citizen of the Dominion of Canada, and resident of Winnipeg, Province of Manitoba, Canada, have invented certain new and useful Improvements in Harness Girth-Connecting Means, of which the following is a specification.

This invention relates to improvements in harnesses particularly adapted for use in hitching or harnessing a horse or team of horses and more particularly relates to the girth connecting means of such harnesses.

Harnesses of ordinary construction are usually provided with a one-piece girth, having one end secured to the harness upon one side of the horse. The other end of this girth passes under the horse (just back of the front legs) through a loop in the martingale, or neckyoke strap, and thence to the other side where it is detachably connected to the harness. It is also customary in harnesses provided with this type of girth, to have the breeching straps detachably connected to the rear end of the martingale. This connection is usually effected by means of snaps or hocks on the ends of the breeching straps, to engage a suitable ring or loop, on the rear end of the martingale. Therefore, when it is desired to remove such a harness from a horse, three disconnections must be made in the harness beneath the horse before it can be removed, i. e., the girth must be disconnected from one side of the harness and the two breeching straps must be released from the end of the martingale.

By the employment of the novel girth connecting means featured in this invention, the girth and the two breeching straps may be connected to the martingale by a single operation, and, in like manner, may be separated therefrom. The invention is very simple and inexpensive in construction, providing a girth connecting means which may be quickly and readily manipulated without loss of time and one which may be used in connection with practically all draft harnesses.

The specific object of this invention, therefore, is to provide an improved girth connecting means adapted for use in connection with draft harnesses which may be quickly and readily connected or disconnected by a single operation.

In the drawings:

Figure 1 is a plan view of a portion of a harness, showing the improved connecting means provided for connecting the girth and the breeching straps to the martingale: 60

Figure 2 is a vertical sectional view on the line 2—2 of Figure 1, showing the connecting means in locking position;

Figure 3 is a bottom view of the connecting means, such means being shown in unlocking position; and

Figure 4 is a cross sectional view on the line 4—4 of Figure 1.

Other objects of the invention will more fully appear from the following detailed description and the accompanying drawings, and will be pointed out in the annexed claims.

In the drawings, there has been disclosed 75 a structure designed to carry out the objects of the invention but it is to be understood that the invention is not confined to the exact features shown, as various changes 80 may be made within the scope of the claims 85 which follow.

In the selected embodiment of the invention here shown for purposes of disclosure, there is illustrated a portion of a harness comprising the breeching or quarter straps 85 11 and 12, girth sections 13 and 14 and the martingale or neckyoke strap 15. The breeching strap 11 and girth section 13 are preferably secured to a metallic rectangular frame 16 by means of an integral loop 90 17, provide on one side thereof and the end bar 18 of the frame, as shown in Figure 1.

Suitable integral guide bars 19 and 21 are provided upon the upper portion of 95 the frame, preferably in spaced relation thereto, as indicated in Figure 2. An integral cross bar 22 is also provided. This cross bar is preferably in horizontal alignment with the frame 16 and loop 17, and is 100 substantially midway between the guide bars 19 and 21. Opposed dogs 23 are pivotally mounted upon the lower portion of the frame 16, by pivot pins or studs 24 secured thereto, and are yieldably held in the 105 position shown in Figure 3, by means of a suitable spring 25, preferably mounted between the two dogs upon a depending lug 26, provided upon cross bar 22 of the frame 16. V-shaped groove 27 is preferably 110 provided upon the inner edge of each dog to receive the ends of the spring 25.

These dogs are preferably provided with upwardly extending integral lugs 28, which are adapted to engage opposed notches 29 provided upon a flattened head or tongue 31 for the purpose of securely locking such head in the frame 16, when inserted therein. The tongue 31 is preferably integrally formed upon one end of a suitable shank 32. This shank also has a small frame 33 pivotally connected or hinged to its opposite end, as indicated in Figures 1 and 2. The girth section 14 is preferably secured to this frame while the breeching strap 12 is secured to an integral loop 34 provided upon one side of the frame 33. The forward end of the tongue 31 is also preferably beveled, as indicated at 35, for the purpose of moving the lugs 28 outwardly against the tension of the spring 25, when the tongue is inserted 20 therebetween.

Thus, when it is desired to connect the girth and the breeching straps to the martingale after the harness has been placed upon the horse, it is only necessary to grasp 25 the shank 32 with one hand and thrust the tongue 31 through the usual loop, provided at the rear end of the martingale. The user will then reach under the horse with his other hand and grasp the frame 16. The 30 tongue 31 will be inserted in the frame until the lugs 28 provided upon the dogs or jaws 23, engage the notches 29 on each side of the tongue, thereby securely locking such tongue in the frame and also positively preventing it from accidentally becoming disengaged therefrom.

To disconnect the girth and also the breeching straps from the martingale, it is only necessary to disengage the lugs 28 from 40 the notches 29, thereby releasing the tongue 31 from the frame 16.

Disengagement of the lugs 28 from the notches 29 is effected by exerting a slight inward pressure upon the rounded ends of the jaws, thus moving the lugs 28 outwardly and releasing the tongue and allowing it to fall and the loop of the martingale to slip off and become separated from the girth.

I claim as my invention:

1. A harness girth connecting means comprising interlocking separable members having means for connection respectively with the ends of the girth, one of said members being adapted for connecting the martingale strap thereto and releasing it when said members are separated.

2. A harness girth connecting means comprising a tongue having means for connection with one end of a girth, and a frame having means for connection with the other

end of the girth, and also having means for interlocking with said tongue, said tongue being adapted for connecting the martingale strap thereto.

3. A harness girth comprising a tongue 65 having means for connecting one end of the girth and one of the breeching straps thereto, a frame having means for connecting the other end of the girth and the other breeching strap thereto and also having means for 70 interlocking with said tongue to temporarily secure said tongue and frame together.

4. A harness girth connecting means comprising a shank having means at one end for connection with one end of the girth and 75 provided with a tongue at its opposite end, said tongue and shank being adapted to pass loosely through a loop in the martingale strap, a frame having means for connection with the other end of the girth, and means 80 in said frame for interlocking with said tongue and temporarily securing said shank to said frame, said shank and tongue when disengaged from said frame allowing the martingale strap to become separated therefrom.

5. A harness girth connecting means comprising members adapted for engagement one with the other for detachably connecting the ends of a girth attached respectively 90 to said members in the rear of and adjacent the forelegs of the animal, said members being adapted respectively for connecting the breeching straps thereto.

6. A harness girth connecting means comprising a shank having loops for connection respectively with one end of a girth and one of the breeching straps, said shank having a tongue formed thereon and adapted to pass loosely through a loop in the martingale strap, a frame having loops for connection respectively with the other end of a girth and the other breeching strap, and spring-pressed means mounted in said frame for interlocking with said tongue, said tongue and shank when released allowing the separation of said girth and breeching straps and said martingale strap.

7. A harness girth connecting means comprising members adapted to interlock one 110 with the other, for connecting the ends of a girth, said members being adapted for connecting the martingale strap and the breeching straps respectively thereto, and releasing the martingale strap when said members are separated.

In witness whereof, I have hereunto set my hand this sixth day of March, 1923.

MARCUS RAY COWELL,
